alignment with bottom panel 19, as shown in Fig. 5. In addition, a tab 32 attached to the lower edge of rear panel 17 extends rearwardly thereof and rests on the table to support the carton in display position.

When the carton is in shipping position, the upper edges of the articles are covered by a cover panel 33. Cover panel 33 is hinged to the upper edge of rear panel 17. Cover panel 33 includes a downwardly extending flap 34 which extends inside the front panel as shown in Fig. 2 when the carton is used as a shipping container. This portion of the cover panel is attached to upward extensions 36 of the side panels by a revenue stamp 37 of the type usually required for cartons of cigars or the like. When the shape of the carton is modified for use as a display container, portion 34 extends behind the articles as shown in Fig. 5. The free edge of portion 34 is provided with a pair of spaced notches 38 forming tabs 39, 40, and 41. Tab 39 extends into the slot 27 in the rear panel. As shown in Fig. 1, cover panel 33 is provided with a scored line 39' along which it bends when in shipping position and a second scored line 41 along which it is folded when in display position. As indicated, a portion of line 41 is a line of cut.

Stamp 37 forms a sealing strip which holds the carton in shipping position until the carton is to be opened and shifted to shipping position. The stamp is broken when the carton is opened to release the cover panel.

When the carton is used as a shipping container, all corners are square and the carton can readily be packed in an appropriate shipping case. When the shape of the carton is to be modified so that it may be used as a display holder, stamp 37 is broken and the end portion of the flap 34 is placed behind the articles. At the same time, the side panels are pushed downwardly until lower edges 29 and 30 thereof are in the plane of the bottom panel. When the carton shape is so modified, the articles therein slope rearwardly and are plainly exposed to view, as shown in Fig. 5.

Blank 12 differs from blank 10 in that triangular flaps 42 and 43 are hinged to lower edges of the side panels. As shown in Fig. 6, when the carton formed therefrom is set up in display position, flaps 42 and 43 extend outwardly from the side panel so that the carton is supported at the sides and rear when in display position. When this carton is in shipping position, flaps 42 and 43 are aligned with the side panels and lower edges 44 and 45 of the flaps are flush with the bottom panel. Flaps 42 and 43 are right triangular in shape. Rear edges of these flaps

are in alignment with side edges of the rear panel when the carton is in shipping position. Edges 44 and 45 of these flaps are perpendicular to the rear edge, as shown in Figs. 1 and 6.

5 The cartons can quickly and easily be shifted from shipping to display position, and, when in display position, display the contents in a proper sloping position.

10 The cartons shown are subject to structural modification without departing from the spirit and scope of the appended claim.

Having described my invention, what I claim as new and desire to secure by Letters Patent is:

15 A display and shipping carton formed from a one-piece blank of sheet material which comprises a front panel, side panels and a rear panel, the lowermost edges of the side panels extending at an acute angle to the front panel and an obtuse angle to the rear panel, a bottom supporting panel hinged to the top edge of the front panel, said bottom supporting panel being of the same length as the front panel and extending downwardly inside thereof, a bottom panel hinged to the lower edge of the bottom supporting panel, the depth of said bottom panel being equal to the distance between the front and rear panels, a panel hinged to the rear edge of the bottom panel for supporting the same, the rear panel having a transverse slot between the ends thereof, there being a tab cut from the rear bottom supporting panel and extending downwardly through said slot, the rear panel sliding along the rear bottom supporting panel in face-to-face relation therewith, between a display position in which the lower edges of the side panels are in the plane of the bottom panel and a shipping position in which the bottom panel is perpendicular to the front and rear panels and at an angle to the plane of the bottom edges of the side panels, the tab binding in the slot when the bottom panel is in shipping position.
